Inventor

UNITED STATES PATENT OFFICE.

DONALD S. BARROWS, OF ROCHESTER, NEW YORK, ASSIGNOR TO THE T. H. SYMINGTON COMPANY, OF NEW YORK, N. Y., A CORPORATION OF DELAWARE.

JOURNAL BOX.

Application filed August 21, 1922. Serial No. 583,212.

To all whom it may concern:

Be it known that I, DONALD S. BARROWS, a citizen of the United States, residing at Rochester, in the county of Monroe and State of New York, have invented certain new and useful Improvements in Journal Boxes; and I do hereby declare the following to be a full, clear, and exact description of the invention, such as will enable others skilled in the art to which it appertains to make and use the same.

My invention relates to journal boxes and, generally stated, involves the provision of a renewable wear plate or liner detachably connected to the journal box of a railway car and means for lubricating the pedestal guides.

The principal feature of the present invention, particularly stated, consists in providing a wear plate adapted to be engaged by a portion of the journal box adjacent an oil or lubricating conduit provided on the journal box and adapted to convey lubricating material to the wearing surface of the plate.

Another object of the invention is to provide in combination a journal box formed with a portion for conveying lubricating material to the wearing surface of a renewable pedestal way liner, said liner being provided with a portion adapted to be engaged by the outer edge of said journal box portion for rendering the joint between said liner and journal box portion smooth and leak-proof against oil or other lubricant finding its way between the back side of the liner and the journal box wall.

The invention further consists in the provision of a journal box renewable pedestal way liner which can be inexpensively manufactured and easily attached to a journal box adjacent an oiling cavity formed in said box.

There are other features of the invention as will more clearly appear from the detailed description taken in connection with the accompanying drawings in which

Figure 1 is a view in side elevation of a railway car journal box showing my improved wear plate applied.

Figure 2 is a vertical sectional view on the line 2—2 of Figure 1, through one half of the journal box and oil reservoir at the top thereof, the other half being a duplicate of

the construction shown, as will be understood.

Figure 3 is a detail plan view of a portion of a journal box showing the liner applied.

Figure 4 is a detail vertical central sectional view through the upper portion of the journal box shown in Figure 1.

Figure 5 is a detail vertical sectional view through the portion of the journal box constructed to convey the lubricating material from the reservoir to the wearing surface of the liner, the liner being shown in attached position prior to the peening engagement of the outer edge of said journal box portion with the liner.

Figure 6 is a view similar to Figure 5 but showing the outer edge of the journal box portion engaged with the liner.

Referring to the drawings in which similar reference characters designate corresponding parts in the several views, a railway car journal box is indicated by the numeral 1, said journal box being provided with a top wall 2 in which is formed the seat 3 adapted to receive the cushioning element, and the usual bottom wall 4. The top wall is provided with an oil reservoir 5, the oil or other lubricant being contained within said reservoir or cavity by means of the upstanding surrounding wall portion 6. In the form of journal box shown I have provided a plurality of oil reservoirs, one on each side of the cushioning element, although it will be understood that a single reservoir may be used in some constructions.

Provided near or at the bottom of each reservoir, is an opening 7, said opening being provided with a wall portion 6 and an adjacent projection or boss 8 extending from the side wall of the journal box a distance substantially equal to the thickness of the wear plate 9, as clearly shown in Figure 5. The opening or perforation 7 in the projection 8 serves to establish communication between the oil reservoir and the wearing surface of the liner. The outermost edge of the projection 8 is provided with a flange 10, said flange forming a portion adapted to be preferably peened against the wear plate.

The wear plate 9 is provided near its upper end with openings 11, said openings being provided to permit the wear plate being fitted over the projections 8, as best shown

2
in Figure 1. The openings 11 are each preferably of slightly larger diameter than the projections or bosses 8, thereby providing a relatively small surrounding space between the projection and the wear plate when the latter is first applied, as shown in Figure 5. This space is subsequently filled by causing the flange 10 to engage the wear plate by a peening, pressing, or other operation.

The flange 10 is preferably peened flush with the wearing surface of the liner, the outer face of the projection 8 surrounding the oil conduit 7 also being preferably flush with said wearing surface, as shown in Figure 6. By this construction the joint between the projection and the liner is rendered tight and all tendencies of the lubricant to find its way between the journal box and liner are prevented.

The wear plate is shown as formed with two openings 11, each of said openings being located relatively close to adjacent flanges 12 of the plate. In the type of journal box shown the liner is cut away intermediate said openings, as indicated by the numeral 13, so as to fit the journal box side wall beneath the offset portion therein provided for the clearance of the equalizer bar, 30 not shown.

Means for detachably connecting the wear plate to the journal box includes the upper bendable extensions 14 forming tongues or tangs adapted to be bent over the upper edge of the wall portion, said tangs extending downwardly into the oil cavities and terminating near the openings 7. A bendable extension 15 is formed on the lower edge of the liner, said extension forming a tongue or tang adapted to be bent around the lower edge of the journal box side wall, as shown. Other types of attaching means may be utilized, as will be understood.

From the foregoing it will be obvious that 45 I have produced a comparatively simple and renewable liner plate or liner for a pedestal way and means for effectively lubricating the same in a direct and economical manner.

I claim:

- 50 1. The combination with a railway car journal box having a pedestal guide way and oil reservoir, of a wear plate or liner for said guide way, and means including a perforated projection provided on the side wall of the journal box adapted to engage the liner, the perforation serving to conduct lubricating material from said reservoir to the wearing surface of said wear plate.
- 55 2. The combination with a railway car journal box having a pedestal guide way, a reservoir adapted to receive lubricating material, of a wear plate for said guide way, and means including a portion of said journal box adapted to be fitted against said wear plate by peening, said portion serv-

ing to establish communication between the reservoir and wearing surface of the wear plate and form a tight joint to prevent the passage of the lubricant between the journal box and wear plate.

70 3. The combination with a railway car journal box having a pedestal guide way and a reservoir adapted to receive lubricating material, of a wear plate for said guide way, and means including a portion of said journal box adapted to be engaged by the wear plate and also serving to establish communication between the reservoir and wearing surface of the wear plate, said portion forming a relatively tight joint with the wear plate whereby any tendency of the lubricating material to find its way between the journal box and wear plate is prevented.

80 4. The combination with a railway car journal box having a pedestal guide way and a reservoir adapted to receive lubricating material, of a wear plate for said guide way, and means including a portion of said journal box having a flange for engaging the wear plate, said flange being adapted to be moved against the wear plate for forming a tight joint therewith, said means also serving to establish communication between the reservoir and wearing surface of the wear plate.

85 5. The combination with a railway car journal box having an oil reservoir, of a wear liner provided with an opening, and means including a projection carried by the journal box and having an opening for establishing communication between said reservoir and the wearing surface of the liner, said projection being adapted to enter the opening in the liner and having an outer edge portion arranged to form a relatively tight joint between said opening in the liner and said projection.

90 6. The combination with a railway car journal box having an oil reservoir, of a wear liner provided with an opening, means for establishing communication between said reservoir and the wearing surface of the liner, and means including a portion of the journal box adapted to enter the opening in the liner to form a relatively tight joint therewith.

95 7. The combination with a railway car journal box having an oil reservoir, of a detachable liner provided with an opening, means including an opening in the wall of the journal box for establishing communication between said reservoir and the wearing surface of the liner, and a projection surrounding said opening in the wall of the journal box and arranged to enter the opening in the liner, said projection terminating flush with the wearing surface of the liner and having a portion adapted to engage said liner and form a tight joint therewith.

8. The combination with a railway car journal box having an oil reservoir, of a detachable wear liner provided with an opening, means including an opening in the 5 wall of the journal box for establishing communication between said reservoir and the wearing surface of the liner, a projection adjacent the opening in the wall of the journal box arranged to enter the opening 10 in the liner, and a flanged portion on said projection adapted to be peened flush against the wearing surface of the liner.
9. The combination with a railway car journal box having an oil reservoir, of a detachable wear liner provided with an opening, means including an opening in the wall 15 of the journal box for establishing communication between said reservoir and the wearing surface of the liner, and a projection adjacent the opening in the wall of the journal box arranged to enter the opening 20 in the liner, said projection having a portion adapted to be peened flush against the wearing surface of the liner and form a 25 relatively tight joint therewith.
10. The combination with a railway car journal box having an oil reservoir at the

top thereof, of a wear plate provided with an opening at the top thereof, a projection on said journal box having an opening 30 therein for establishing communication between the oil reservoir and the wearing surface of the wear plate, said projection extending through the opening in the wear plate and forming a relatively tight joint 35 therewith.

11. The combination with a railway car journal box having a pedestal guide way and oil reservoir, of a wear plate provided with an opening, means for detachably connecting said wear plate in said guide way, said means including a bendable tongue 40 adapted to engage the wall of said reservoir, a projection on said journal box provided with an opening therethrough and discharging from the oil reservoir to the wearing surface of the wear plate, said projection extending through the opening in the wear plate and forming a relatively tight joint therewith. 45

In testimony whereof I affix my signature.

DONALD S. BARROWS.
